MEANS FOR AUTOMATICALLY INJECTING
FUEL INTO ENGINES

Earl B. Marr, Santa Clara, Calif.

Application January 5, 1948, Serial No. 502

1 Claim. (Cl. 261—65)

1

This invention relates to automatic fuel injection means for internal combustion engines.

An object of my invention is to provide auxiliary means for automatically admitting fuel to an engine when additional fuel is needed for its operation.

Another object of my invention is to provide auxiliary fuel delivery means for internal combustion engines which automatically admits a mixture of air and fuel to the intake manifold when the suction pressure therein is decreased because of the failure of the usual carburetor means to deliver sufficient quantities of fuel to meet the load requirements.

Other objects and advantages of my invention will be pointed out hereinafter, or will be indicated, or will be obvious to one skilled in the art upon an understanding of the present disclosure. For the purpose of this application I have elected to show herein certain forms and details of auxiliary means for delivering fuel to an internal combustion engine representative of my invention; it is to be understood, however, that the embodiment of my invention herein shown and described is for the purpose of illustration only and that therefore it is not to be regarded as exhaustive of the variations of the invention.

In the accompanying drawings:

Fig. 1 is a side elevation of my improved auxiliary means for automatically delivering fuel to an engine, showing parts of the latter in section;

Fig. 2 is an enlarged sectional view of the means;

Fig. 3 is a sectional view taken on the line 3—3 of Fig. 2; and

Fig. 4 is a sectional view of a check valve used with my invention.

Referring to the drawings the numeral 1 shows a conventional engine having a fuel intake manifold 2.

My invention is preferably connected to the fuel intake manifold, and it operates independently of the carburetor or other means ordinarily used to supply fuel to the combustion chambers of the engine.

The main operating unit of my invention includes an elongated tubular casing 3 comprising two sections which are joined end to end by threaded means. The outlet end of the tubular casing is connected by means of a threaded nipple 4 to the fuel intake manifold 2, and the opposite end of the said casing has an intake opening 5 for admitting air under atmospheric pressure to the casing during the operation of the device.

2

The interior of the casing is divided into two chambers 6 and 7, preferably of unequal size, by a partition 8, and the said chambers are connected by an opening 9 in the partition so that a mixture of air and liquid fuel may pass from the chamber 6 to the chamber 7 during the operation of the device. The casing 3 is provided as at 10 with an annular inwardly protruding shoulder which is positioned in the chamber 7, the said shoulder forming a valve seat against which the enlarged end portion 11 of a valve element 12 may become positioned to discontinue the flow of fuel through the casing, as will be later described. There is a slight clearance between the periphery of the valve element 12 and the inner surface of the tubular casing to permit fuel to flow through the said casing to the intake manifold when the valve element is unseated with respect to the valve seat 10. The valve element 12 is formed with a tapered end portion having a series circularly arranged radially disposed slots or grooves 13 having their inner closed ends arranged in converging relationship, the said slots forming fuel passages which provide atomizing means for thoroughly mixing the air and fuel before it is discharged into the intake manifold 2. A helical spring 14 engaging at its opposite ends with the discharge end of the casing 3 and with the valve element 12 exerts a predetermined pressure against the latter in a direction whereby its enlarged end portion 11 may be unseated from the valve seat 10 when the suction in the manifold has decreased to a certain extent, as when the engine fails to function properly because of a deficiency in the fuel normally supplied from the carburetor to the combustion chambers.

An externally threaded jet member 15 having a restricted outlet opening 16 extends well into the chamber 6 of the casing 3. A connecting union 17 having a restricted opening 18 connects the jet member 15 with an elbow fitting 19 forming a part of a fuel delivery line 20 leading to a source of fuel, such as a gasoline tank. Connected in the line 20 is a ball type check valve 21 which functions in the usual manner to allow fuel to proceed upwardly through the line 20 but not downwardly in a reverse direction. The arrangement of the check valve in the line 20 at a point substantially spaced from discharge end of the jet 15, makes it possible for a substantial charge of liquid fuel to be maintained in the upper part of the supply line at all times, preparatory to the operation of the device when conditions in the engine require an increase in the fuel supply.

In the normal operation of the engine the suction in the fuel intake manifold 2 is ordinarily

such that the atmospheric pressure against the valve element 11 is utilized to overcome the tension of the spring 14 and cause the valve element 11 to assume a position closing the opening through the casing 3. When such a condition prevails there is no fuel supplied to the intake manifold by the present auxiliary fuel delivery means. When the suction in the fuel intake manifold decreases to a certain extent as when the engine requires a greater amount of fuel for its operation than is then being supplied by the usual fuel delivery means, the spring 14 functions to unseat the valve element 12 and allow a mixture of fuel and air to pass through the casing to the manifold. It is to be noted that the pressure exerted against the valve element 12 by the spring 14 is sufficient to overcome the atmospheric pressure in the opposite direction upon the said valve element when the suction pressure in the intake manifold decreases to a predetermined extent. In this regard the force of the spring 14 against the valve element 12 is not sufficient to overcome the forces exerted in the opposite direction upon the said valve element by the atmospheric and suction pressures when the engine is operating in the normal manner, but when the suction decreases to a predetermined extent the spring operates to automatically unseat the valve and thereby permit the mixture of air and fuel to be drawn through the casing into the fuel intake manifold.

In operation it is to be noted that the liquid fuel proceeding upwardly through the line 20 passes through the Venturi-like opening 18 into the jet member 15. It then passes through the restricted outlet opening 16 in the jet member 14 into the stream of moving air then entering the casing through the air inlet opening 5. The fuel entering and mixing with the air stream proceeds through the opening 9 into the chamber 7 past the enlarged portion 11 of the valve element 12, through the radial slots 13 in the latter and thence into the fuel intake manifold 2 from whence it is distributed in the usual manner to the combustion chambers of the engine. The vaporization of the fuel and the thorough mixing thereof with the air is assisted by means of the small openings 16 and 9 and the small channels provided by the radial slots 13. Thus when the fuel enters the intake manifold it is suitably vaporized

and prepared for immediate use in the combustion chambers without further mixing or treatment.

What I claim is:

- 5 An auxiliary carburetor for use with an internal combustion engine comprising an elongated casing having two chambers connected end to end, one of the chambers being a mixing chamber and having an air inlet and a fuel inlet arranged at substantially right angles to each other and the other chamber being an atomizing chamber and having a fuel inlet at one end in communication with the mixing chamber and a fuel outlet at its opposite end adapted to be connected to the intake manifold of an engine, the 10 said casing having a valve seat arranged in the atomizing chamber, a valve member mounted in the atomizing chamber and arranged for movement between a closed position seated against 15 the valve seat and an open position spaced from said valve seat, the said valve member having a conical end portion formed with circularly arranged spaced radial slots, the said slots having converging closed inner ends, and a compression 20 spring mounted in the atomizing chamber in operative engagement with the valve member for urging the said valve member toward its open position, the said valve member being adapted to be actuated to open or closed positions in accordance with fluid-pressure differentials formed in 25 the operation of the engine.
